UNITED STATES PATENT OFFICE.

ALEXANDER ADAMSON, OF AKRON, OHIO.

VULCANIZER.

1,013,716.

Specification of Letters Patent.

Patented Jan. 2, 1912.

Application filed August 12, 1911. Serial No. 643,692.

To all whom it may concern:

Be it known that I, ALEXANDER ADAMSON, a citizen of the United States, residing at Akron, in the county of Summit and State 5 of Ohio, have invented new and useful Improvements in Vulcanizers, of which the following is a specification.

This invention relates to improvements in vulcanizers of the type shown and described 10 in United States patent granted to me April 4, 1911, and numbered 988,295.

The object of the invention is to provide an efficient device to render the rotation of 15 the vulcanizer-cover comparatively easy during the interlocking of the cover with the vulcanizer-head and its removal therefrom.

As described in the before mentioned patent, the open end of a vulcanizer of this 20 type is provided with a plurality of inwardly extending integral lugs below which is a shoulder provided with a packing-ring to constitute a seat for the cover of the vulcanizer and the latter is provided on its lateral 25 face with a plurality of laterally-projecting lugs which are arranged to be interlocked behind the lugs on the open end of the vulcanizer by imparting to the cover a partial rotation. Experience has demonstrated that 30 when the cover of the vulcanizer is initially seated upon the packing-ring in the shoulder of the vulcanizer-head its rotation to cause the lugs of the two members to interlock is a matter of considerable difficulty 35 and hence, the primary object of this invention is to provide means which will temporarily and yieldingly sustain the weight of the vulcanizer-cover during its placement in such a way as to render its rotation compar- 40 atively easy, and at the same time so construct the sustaining means as to in no wise interfere with the successful operation of the device.

With the foregoing and other objects in 45 view, the invention consists in the novel construction, combination and arrangement of parts constituting the invention to be hereinafter specifically described and illustrated in the accompanying drawings which 50 form a part hereof wherein is shown the preferred embodiment of the invention, but it is to be understood that changes, variations and modifications can be resorted to which come within the scope of the claims 55 herein appended.

In the drawings in which similar refer-

ence numerals indicate like parts in the different figures, Figure 1, is a plan view of a vulcanizer of the type mentioned showing my improvement in operative relation therewith; Fig. 2, is a vertical, sectional view on line X of Fig. 1; and Fig. 3, is a vertical sectional view enlarged, of a part of a vulcanizer and cover approximately on line Y of Fig. 1.

Referring to the drawings in detail, the reference numeral 1 denotes the body of a vulcanizer which usually comprises a hollow cylinder open at one end and provided 60 interiorly with a ram or plunger (not shown), on which are placed a tier of separable molds in which are placed the articles to be vulcanized. The function of the ram or plunger being to compress the parts of the molds together, and the tier of molds 65 against the under face of the cover of the vulcanizer to hold the parts of the molds firmly together during the vulcanizing process. The ram or plunger is usually operated by hydraulic force and the articles 70 arranged to be used are cured through the medium of live steam introduced into the cylinder. Around the open end of the vulcanizer 1 is an annular head 2 secured to the cylinder by means of hold-fast devices 75 80. The upper end of the head 2 is provided with a laterally-extending ledge 4 surrounded by an upwardly-extending annular flange 5 on the inner face of which are inwardly-extending spaced lugs 6. In the 85 upper face of the ledge 4 is an annular channel to receive a packing-ring 7.

The cover of the vulcanizer comprises an inverted saucer-shaped member 8 across the interior of which extends a plurality of 90 strength-giving radial ribs 9 and it has in the center a threaded opening to receive an eye-bolt 10 by which the cover may be lifted free from the vulcanizer when desired. The lateral face of the cover is provided with a 100 series of laterally-projecting lugs 11 spaced from each other a distance slightly greater than the width of the lugs 6 and the width of the lugs 11 is slightly less than the width of the spaces between the lugs 6 to permit 105 the lugs 11 to freely pass through the spaces existing between the lugs 6 in seating the cover. The lugs 11 are arranged to be passed through the spaces between the lugs 6 and after so doing, the cover is given a 110 partial rotation to interlock the lugs 11 behind the lugs 6. When the cover 8 is being

lowered it is usually placed upon the uppermost mold of a tier of molds positioned on the upper face of the ram or plunger and naturally seats upon either the ledge 4 or the packing-ring 7 during its downward movement and experience has clearly demonstrated that it requires a great effort to sufficiently rotate the cover to cause the lugs 11 to interlock behind the lugs 6 and in order to obviate this difficulty, the following mechanism is provided: The top of the cover 8 is provided with a plurality of steps or seats 12 on which are loosely pivoted a plurality of radial bars 13 held in position by means of hold-fast devices 14. These bars 13 extend beyond the lateral face of the cover and their outer ends are rounded to constitute axles for flanged-wheels 15 which are held in position on the bars 13 by some hold-fast devices such as nuts 16. The wheels 15 are so positioned that when the cover is lowered they will run on the upper face of the flange 5 of the vulcanizer-head with the flanges of the wheels extending laterally over the flange to serve as guiding means when rotating the cover. Below the bars 13 and preferably integral with the cover 8 are upwardly-extending lugs 17 provided with vertical, threaded openings to receive the lower ends of threaded pins 18, projecting upwardly through suitable apertures in the bars 13 the upper ends of which bear adjusting-nuts 19 for holding and changing the position of washers 20 which are apertured to be freely slidable on the pins 18. Between the washers 20 and the upper faces of the bars 13 are coiled springs 21 the normal tendency of which is to force the bar downwardly onto the lugs 17 to resist the upward movement of the bars when the cover has been lowered to position with the wheels 15 resting on the flange 5. The bars 13 and wheels 15 will preferably be arranged at equal distances apart and three are customarily employed as being the best number for accomplishing the function of supporting the cover equally at all points and permit its easy rotation.

In operation, the cover is lifted off from the vulcanizer-head and a number of filled molds placed upon the upper face of the ram or plunger after which the cover is lowered and placed upon the uppermost mold. The plunger is then lowered and its position is such that the lugs 11 will pass through the spaces existing between the lugs 6. After the lugs 11 have passed downwardly beyond the under faces of the lugs 6 the wheels 15 will seat upon the upper face of the flange 5 and prevent the under surface of the cover from touching either the shoulder 4 or the packing-ring 7. The weight of the cover will slightly overcome the resistance of the springs 21 so that the bars 13 will be slightly raised above the lugs

as shown in Fig. 3, however, the strength of the springs 21 will be sufficient at all times to prevent contact between the under face of the cover and the shoulder or packing-ring of the head. The cover is then easily given a partial rotation, preferably by inserting a bar (not shown), between a pair of lugs 22 formed on the upper face of the cover for that purpose. As soon as the cover has rotated sufficiently to cause an interlocking engagement between the lugs 11 and 6, the ram with its load of molds is forced upwardly against the under face of the cover which constitutes an abutment against which they are pressed for holding the parts of the molds together during the vulcanization of the articles contained within them. After vulcanization the ram is lowered and the cover is given a partial disengaging rotation and is then lifted in unison with the tier of molds out of the vulcanizer.

In practice, I prefer to make the packing-ring of the type shown and described in the Letters-Patent hereinbefore referred to, that is to say, of the expansible type wherein the packing-ring is forced upwardly against the under face of the cover by means of a fluid under pressure, but as this type of packing-ring is well known, it is thought that a further description thereof is believed to be unnecessary.

I claim:

1. The combination with a vulcanizer and a cover therefor each provided with a series of spaced lugs, the lugs on said cover adapted to be passed through the spaces between the lugs on the said vulcanizer and to be interlocked behind the latter when the cover is given a partial rotation, of rollers carried by said cover and engaging said vulcanizer adapted to permit of the easy rotation of said cover during the interlocking operation.

2. The combination with a vulcanizer having at its open end a series of spaced lugs, a cover for said vulcanizer having a series of spaced complementary lugs adapted to interlock with the lugs on said vulcanizer, of rollers carried by said cover and engaging said vulcanizer adapted to permit the easy rotation of said cover during the interlocking operation.

3. The combination with a vulcanizer and a cover having complementary interlocking portions, said operation of interlocking embodying a partial rotation of said cover, of a plurality of rollers carried by said cover and adapted to engage the upper face of said vulcanizer for permitting the easy rotation of said cover during the operation.

4. The combination with a vulcanizer and a cover therefor which are provided with portions adapted to interlock, said interlocking operation involving a partial rotation of said cover, of a plurality of flanged rollers

suitably mounted on said cover and running on the upper wall of said vulcanizer for permitting the easy rotation of said cover and guiding the same during the interlocking operation.

5. The combination with a vulcanizer and a cover therefor each provided with complementary portions adapted to interlock, the interlocking operation involving the partial 10 rotation of said cover, of a plurality of radial arms carried by said cover, rollers on said arms adapted to run on the upper face of said vulcanizer to permit the easy rotation of said cover during the interlocking 15 operation.

6. The combination with a vulcanizer and a cover therefor each provided with complementary portions adapted to interlock, the

interlocking operation involving a partial rotation of said cover, of a plurality of 20 loosely pivoted radial arms mounted on said cover, springs tending to force said arms downwardly, means for adjusting the tension of said springs and rollers mounted on said arms and adapted to run on the upper 25 wall of said vulcanizer to permit the easy rotation of said cover during the interlocking operation.

In testimony whereof I have hereunto set my hand in presence of two subscribing witnesses.

ALEXANDER ADAMSON.
